JOSEPH McCONNELL, OF IOWA CITY, IOWA.

Letters Patent No. 69,282, dated September 24, 1867.

IMPROVEMENT IN VALVES FOR STEAM ENGINES.

The Schedule referred to in these Letters Patent and making part of the same.

TO ALL WHOM IT MAY CONCERN:

Be it known that I, JOSEPH McCONNELL, of Iowa City, in the county of Johnson, and State of Iowa, have invented a new and useful Improvement in Steam Engines; and I do hereby declare that the following is a full, clear, and exact description thereof, which will enable those skilled in the art to make and use the same, reference being had to the accompanying drawings, forming part of this specification.

This invention relates to a new and improved valve motion in the steam engine, the principal novelty of which consists in opening and closing the ports of the engine cylinder by operating two cylinder valves at each end of the engine cylinder, (one within the other,) the inner valve being a cut-off valve; and the invention consists in the manner in which these valves are arranged and operated, and in the device for rendering the inner valve a variable cut-off, controlled by the speed of the engine through the governor, as will hereinafter be described.

Figure 1 represents a side view of the engine, showing the steam-chests at each end of the cylinder, and the arrangement for operating the cut-off valve.

Figure 2 is a plan or top view of the same, showing the main shaft, the eccentrics, and their rods, attached to the cranks of the oscillating valve stems.

Figure 3 is a vertical section of fig. 2 through the line *x x*.

Figure 4 is a vertical section of fig. 3 through the line *y y*.

Figure 5 is another vertical section of fig. 2 through *x x*.

Similar letters of reference indicate corresponding parts.

A represents the engine cylinder, B the main shaft, C the piston, and D the piston-rod; E is the pitman, which is connected with the cross-head D', and with the fly-wheel B' of the main shaft; F' F' are the eccentrics on the main shaft, and G G' are the eccentric-rods.

There is no particular novelty in the engine or the parts connected with it, so far as we have lettered the same. The main features of the improvement and invention, as before stated, consist in the construction, arrangement, and operation of the valves, which we will now proceed to describe.

H H are the steam-chests, cylindrical in form, and situated at each end of the cylinder, and, as seen in the drawing, they are placed at right angles or transversely to the cylinder. Within each of these steam-chests there is a cylinder oscillating valve, the stems of which are seen in fig. 2, marked J J. Each stem has a short crank, *i i*, with wrists, and they are both operated by the eccentric F and rod G, by being connected together by the rod *k*. These valves are open at their opposite ends and on their sides, as seen in the drawing, figs. 3 and 5. These are the main steam-valves, each having a slot aperture opposite the open part. They are marked *n n*. The slot apertures, as the valves are rolled or oscillated, admit steam to the cylinder and exhaust it therefrom in a manner similar to the ordinary rolling valve. The steam is exhausted into an orifice which is cast in the cylinder, seen at *o*, fig. 4, which orifice communicates with a chamber in the bed-plate of the engine, as seen at *m*. The course of the exhaust steam is indicated by the arrow in fig. 3. The cut-off valves are placed within the steam-valves *n*, where they are oscillated, the same as the steam-valves are in the steam-chest. In the figs. 3 and 5 the ends of these cut-off valves are seen, marked *p*. They also have stems and cranks, which are seen in figs. 1 and 2. The stems are marked *r*; the cranks are marked *s*. These valves are oscillated by the eccentric F' and rod G', attached to a rock-shaft, T. This rock-shaft passes transversely over the engine cylinder, and has on its end a slotted arm, *u*, a side view of which is seen in fig. 1. *v v* are connecting links, which are loosely attached to the cranks *s* by screw-bolts, and which have wrist-pins *x* on their inner ends, the collars of which are inside of the links *v*. Between the pins the collars are flattened, so that they will enter the slots on the arms *u*, as seen in fig. 1. This slotted arm *u*, being attached to the rock-shaft T, which is operated by the eccentric F', operates the cut-off valves *p p*. The amount of steam which these valves cut off or let on depends upon the extent of their oscillating movement or throw, and the throw, of course, depends upon length of the cranks *s*, and the position of wrist-pins *x* in the slots of the arm *u*. The position of the pins *x* in the slots may be controlled by the governor of the engine, the rod of which may be connected with the pins *x* by a suitable bridle, (seen in red,) whereby the pins can be slipped up and down in the slots as the balls of the governor rise or fall by the variations of the speed of the engine. It is thus made a self-adjusting variable cut-off. The steam pipe from the boiler is connected with the pipe *h* at *h'*. There are heads on the ends of the steam-chests,

through which the valve-rods pass, marked o' . There may be stuffing-boxes attached to these heads, by which the valve-stems may be packed steam-tight. The rock-shaft T is supported on stands f , as seen in fig. 3. The slotted arm u is fastened to the rock-shaft by a set-screw, or in any suitable manner. Having thus described my invention, what I claim, and desire to secure by Letters Patent, is—

1. The combination and arrangement of the arm u , secured to the end of the rock-shaft T , between the cylinders H , and in the slots of which the wrist-pins x work, connecting the arm u to the valves p , the position of said pins x in the slots being controlled by means of the governor, whereby the throw of the valves p is regulated, as herein shown and described.
2. The valves p , constructed as described, formed in a semicircle, with the pressure of steam applied upon one side, as and for the purpose specified.
3. The arrangement of the cylinders H , main valves and cut-off valves p , transverse shaft T , slotted arm u , connecting-arms v , and cranks s , as and for the purpose specified.

JOSEPH McCONNELL.
